Primary Examiner — Jennifer L Rempfer*Assistant Examiner* — John Patrick G Ribay(74) Attorney, Agent, or Firm — Fross, Zelnick, Lehrman & Sissu, P.C.; Charles T. J. Weigell, Esq.(57) CLAIM

The ornamental design for a handbag as shown and described.

DESCRIPTION

FIG. 1 is a first front perspective view of the handbag showing my new design;

FIG. 2 is a second front perspective view thereof;

FIG. 3 is a back perspective view thereof;

FIG. 4 is a left side perspective view thereof;

FIG. 5 is a right side perspective view thereof;

FIG. 6 is a top perspective view thereof; and,

FIG. 7 is a bottom perspective view thereof.

The whitewashed areas surrounded by broken line depict portions of the article that form no part of the claimed design.

1 Claim, 7 Drawing Sheets(56)
